LOG RACK

Ed Falkenberg, 2150 N. 147th, and Edwin S. Lagoe,
3017 23rd Ave., both of Seattle, Wash.

Filed Dec. 28, 1962, Ser. No. 73,026

Term of patent 14 years

(Cl. D81—18)

Fig. 1.

Fig. 2.

Fig. 3.

Fig. 4.

Fig. 5.

Fig. 6.

Fig. 7.

Fig. 8.

Fig. 9.

FIG. 1 is a view in side elevation of a log rack showing our new design;

FIG. 2 is an isometric view of the log rack of FIG. 1;

FIG. 3 is a view in end elevation of the log rack of FIG. 1;

FIG. 4 is a view in side elevation of a log rack showing a modified form of our new design;

FIG. 5 is an isometric view of the log rack of FIG. 4;

FIG. 6 is a view in end elevation of the log rack of FIG. 4;

FIG. 7 is a view in side elevation of a log rack showing another modified form of our new design;

FIG. 8 is an isometric view of the log rack of FIG. 7; and

FIG. 9 is a view in end elevation of the log rack of FIG. 7.

The logs are shown in broken lines on the drawings for illustrative purposes only.

This application is a continuation-in-part of our co-pending application Serial No. D. 69,258, filed March 14, 1962, and now abandoned.

We claim:

The ornamental design for a log rack, substantially as shown and described.
